9 Claims. (Cl. 178—17.5)

This invention relates to telegraph signaling apparatus and more particularly to telegraph systems for signaling by means of double current cable code signals, that is to say, by means of the Morse code in which the signals consist of electrical conditions which are made to persist for various time intervals. The double current cable code as usually employed in practice makes use of two different kinds of currents or electrical 5 conditions to represent the three signal elements dots, dashes and spaces; for example, a dot is often represented by an electrical condition such as a marking current having a duration of 100 per cent of a signaling interval, a dash by a second 10 electrical condition such as a spacing current having the same duration, and a space is represented by the first electrical condition lasting for 15 50 per cent of a signaling interval followed by the second electrical condition lasting for the re- 20 maining 50 per cent of the signaling interval.

In order to overcome interference in telegraphy and particularly in order to overcome the effects of atmospherics or fading in wireless telegraphy circuits, it is well known to arrange for signals 25 to be automatically repeated from a transmitting station after certain intervals and for the repeated signals to be inter-leaved with the first transmission of the signals and also to arrange for automatic comparison of the original transmission 30 and the repeated signals at a receiving station.

The main object of the present invention is to apply the principle of automatic repetition and subsequent comparison of the repeated signals to double current cable code working.

Thus, according to the present invention, each 35 double current cable code signal is sent once and then sent again after a predetermined period and if desired, a third or even more times. The signals may be sent singly, in which case the signals of the repetition become alternate with the first transmission, or they may be sent in groups. Thus, the double current cable code telegraph 40 system may be arranged to operate in effect on two or more channels, the circuit being allotted 45 to the different channels in sequence and in this case, a signal is transmitted during the periods belonging to one channel and is subsequently automatically repeated; if it is only repeated once, the repeated signal is in effect sent on the second channel, but if repeated more than once, the repetitions are sent in the periods allocated to the channels other than the first channel. For this purpose, the original signal when transmitted is also stored and the storing mechanism is arranged to divest itself of the signals later and

thereby to cause the repetition of the signals during the second or other channel times. At the receiving station, the signal first received is stored for a sufficient time to await the arrival of the repetition or repetitions of the signal when the original transmission and the repetition or repetitions are applied simultaneously to a receiving apparatus for comparison purposes. The storage, both at the transmitting end and at the receiving end, may be effected by storing in condensers by means of suitable synchronously operated switching gear for charging and discharging the condensers. However, in both instances, the signals may be stored electromagnetically, for example by recording the signals 15 on a magnetic medium and subsequently, after a predetermined interval, causing that medium to operate electromagnetic pick-ups or transmitters which, at the transmitting station, cause the repetition of the signal to the line and at the receiving station cause the original received signal 20 to be made available for comparison purposes upon the arrival of the repeated signal. However, any other convenient form of storage means may be employed.

In order that the invention may be clearly understood and readily carried into effect some examples of transmitting and receiving arrangements in accordance with the invention in which the signal is repeated once only will now be more 25 fully described with reference to the accompanying drawings, in which:—

Figure 1 is a circuit diagram of the sending arrangements employing condenser storage;

Figure 2 is a circuit diagram of the receiving arrangements also employing condenser storage; 35

Figure 3 is a diagram corresponding to the lower part of Figure 2, but in which the comparison relays are differently connected;

Figure 4 is a circuit diagram of modified sending arrangements provided with electromagnetic storage; 40

Figure 5 is a similar transmitting circuit provided with relay storage;

Figure 6 is a diagrammatic plan;

Figures 7 and 8 are elevations of details in two 45 positions illustrating mechanical or so-called "metal" storage; and

Figure 9 is a diagram of the connections of a sending apparatus embodying such "metal" storage.

Referring first of all to Figure 1, the sending circuit is similar to that described with reference to Figure 9 of the drawings accompanying Patent No. 1,925,756. Thus, two sets of cable code signal 50

transmitting levers 21, 22 and 27, 28 driven at equal speeds are provided. The primary signal transmitting levers are indicated generally at TS while the delayed transmitting levers are indicated generally at TD. There is also a pair of combining switches C₁, C₂ and a reversing switch RS. These elements are timed or operated in the same phase relationship as described in the said prior patent. The timing of the two sets of transmitting levers TS and TD is as indicated by the circular arrows 1, 2, 3. The timing of the combining switches C₁ and C₂ is indicated by the arrows 4, 5, 6, 7 and is the same as in Figure 9 of the drawings with the said prior patent. This also applies to the timing of the reversing switch RS as indicated by the arrows 8, 9.

In this case, the signal transmitter TS consists of a pair of relays, the coils 10, 11 of which are controlled respectively by the dot and dash mechanism of a cable code transmitter used for transmitting the signals.

The delayed transmitter TD has its coils 12, 13 energized from the signals stored in the storage arrangement. The latter consists of a synchronously driven distributor switch with two sets of stationary contacts 14, 15 which are traversed by pairs of brushes 16, 17, 18, 19. The latter are rotated, for example by means of a phonic motor at such a speed that each makes contact with one of the distributor contacts 14, 15 during the time of one signal period. The brushes 16, 17 are the charging brushes and they make contact at about the middle of a signal period.

The two corresponding contacts of each set 14, 15 are connected to one of the storage condensers, all of which condensers have the opposite plates earthed and connected to the centre of the split battery SB. It will be noted that the charging brush 16 is connected to the tongue 21 of the dash relay of the transmitter TS, while the charging brush 17 is connected to the tongue 22 of the dot relay of the transmitter TS. Therefore, the condensers 20 are charged in turn with a polarity which is positive or negative depending upon whether the signal is a dot, dash or space. Thus, if a space signal is sent, both of the relay tongues 21, 22 will remain against their back butt contacts 23, 24. The contact 23 is connected to the positive of battery SB so that the brush 16 will charge its condenser 20a positively. On the other hand, the contact 24 is connected to the negative end of the battery SB so that the brush 17 will charge its condenser 20b negatively. In the case of a dot signal, the coil 10 draws down the tongue 22 on to the front butt contact 25; the latter is connected to the positive terminal of battery SB, and therefore in this case the brush 17 will charge its condenser 20b also positively. Finally, in the case of a dash signal, the coil 11 of the dash relay draws down its tongue 21 on to its front butt contact 26 so that now brushes 16 and 17 both charge their corresponding condensers 20a, 20b negatively.

The brushes 18, 19 are rotated at the same speed as the brushes 16 and 17 so that they come into contact with the contacts 15 connected to the condensers 20 at a definite interval after these condensers have been charged. Diagrammatically this interval is illustrated as three times the distance between a pair of distributor contacts, but in actual practice, the distributor may have a very large number of contacts, and the

delay may be equal to a large number of signal periods.

When the discharging brushes 18, 19 make contact with segments 15, the condensers 20c and 20d connected to the distributor contacts 15 in contact with the brushes 18, 19 are discharged through these brushes and through the coils 12, 13 of the two polarized relays 12, 13 which in effect form the second cable code transmitter. If a space signal has been stored, the condenser 10 discharges cause the tongues 27, 28 of these two polarized relays to be brought against their spacing contacts 29, 30 although one of the tongues 27, 28, and sometimes both, will already be in contact with the spacing contacts 29, 30. If a dot signal has been stored, the tongue 27 of the dot polarized relay is thrown over to its marking contact 31, while if a dash signal has been stored the tongue 28 of the dash polarized relay is thrown over to its marking contact 32.

It will be noted that the tongues 21, 22 of the transmitting relay TS are connected respectively to the butt contact 33 of the combining switch C₂ and the butt contact 34 of the combining switch C₁, while the tongue 27 of the dot polarized relay 12 is connected to the butt contact 35 of the combining switch C₁ and the tongue 28 of the dash polarized relay 13 is connected to the butt contact of the combining switch C₂. Therefore, the tongues 27, 28 of the two polarized relays control the repetition of the signal to the line L with the delay determined by the period of storage in the condensers 20. The discharge brushes 18, 19, are timed so that the tongues 27, 28 are connected to line in the middle of their signal periods. This is clearly seen by comparing on the one hand, the arrows 2, 5 and 8 and on the other hand, the arrows 3, 7 and 9.

The condensers 20 may be used alternately for storing dots and dashes respectively in which case the dot and dash brushes 16 and 17 are placed on the distributor drum at opposite ends of a diameter. As an alternative, of course, separate banks of condensers may be provided for the dots and dashes.

Referring now to Figure 2 in which a receiving circuit is illustrated, the directly sent signals and the stored signals sent on the two channels have to be separated and the double current cable code signals received from the line are transformed into ordinary cable code. The receiver illustrated in Figure 2 is connected as described with reference to Figure 4 of the drawings accompanying United States Patent No. 2,029,071 dated Jan. 28, 1936. In addition, however, to the apparatus there illustrated, there is mechanism provided at the receiving station for storing the signals as received from the first or original transmission due to the transmitter TS and rendering those signals available when the repeated transmission from the transmitter TD arrives, so that the first or direct transmission and the repeated transmission may be compared directly. In Figure 2 the relays 37, 38, 39, 40 may be regarded as corresponding to the output relays ORA¹, ORA², ORB¹ and ORB² in Figure 4 of the drawings accompanying the said prior specification. Thus, 37 and 39 are the dot receiving relays for the original and repeated signals and 38 and 40 are the corresponding dash relays. When a dot arrives on the original transmission the winding 37 is energized, contacts 41, 42 are closed and a further relay 43 is energized. Similarly, when a dash arrives on the original transmission, the contacts 44, 45 are closed and

an additional relay 46 energized. The tongue 47 of the dot relay 43 is connected directly through a resistance r_1 to the dot charging brush 48, while the tongue 49 of the dash relay 46 is similarly connected through a resistance r_2 to the dash charging brush 50. The storage arrangements here consisting of two sets of contact segments 51, 52, the charging brushes 48 and 50 and the discharging brushes 53, 54, with the condensers 55 are similar to the storage arrangements in the sending apparatus shown in Figure 1, so that the condensers 55 are charged by the pair of brushes 48, 50 to a polarity depending upon whether the first or original transmission sends a space, dot or dash. Thus, it will be noted that when the dot relay 43 is not energized, its tongue rests against the back contact 56 which is connected to the negative terminal of the battery and then the brush 48 charges the corresponding condenser 55 negatively. Similarly, the front contact 57 of the relay 43 is connected to the positive terminal of the battery while the respective back and front contacts 58, 59 of the dash relay 46 are connected to positive and negative ends of the battery.

The discharging brushes 53, 54 lag behind the charging brushes 48 and 50 by the same time period as the discharging brushes 18, 19 of the sending apparatus lag behind the charging brushes 16, 17, and the brushes 53, 54 are connected to energize a pair of comparison relays 60, 61 at the instants when the discharging brushes 53, 54 make contact with the distributor segments 52. Suitable shaping condensers 62 and resistances 63 are connected across the windings on relays 60 and 61.

Corresponding with the pair of comparison relays 60 and 61, there is another pair of comparison relays 64, 65 allocated to the second or repeated transmission and whose windings are energized direct from the tongues 66, 67 and the front contacts 68, 69 of the dot and dash output relays 39, 40 respectively. Therefore, the four comparison relays 60, 61, 64, 65 are energized, the first pair 60, 61 by the direct transmission which has been subjected to storage in the condensers 55, and has therefore been delayed, and the other pair of relays 64, 65 are energized by the repeated transmission. Then as the delay in the direct transmission due to storage in the condensers 55 is the same as the delay of the repeated transmission in the condensers 20 of the sending apparatus, the two pairs of comparison relays 60, 61, 64, 65 are actuated simultaneously by corresponding signals. These four comparison relays are connected to the windings 70, 71 of a pair of final relays. In Figure 2 the connection of the relays 70 and 71 is shown as employed when fading occurs, while in Figure 3 the same relays are shown connected for use when atmospherics are prevalent.

If double current cable code signals are sent over a wireless circuit, it is convenient for the dots to be represented by a power transmission for 100 per cent of a signaling interval, for dashes to be represented by ceasing to transmit power for 100 per cent of a signaling interval, and to represent spaces by transmitting power for 50 per cent of signaling interval followed by ceasing to transmit power for the remaining 50 per cent of the signaling interval. In such a system the result of fading is that dots are missed and extra dashes are received in their place. In Figure 2 the relays 60, 61, 64, 65 are connected to the coils 70, 71 of the final relay

which may in fact be magnets of a perforator in such a way that false operation due to fading only occurs when fading affects equally the corresponding signals in both the original and the repeated transmissions. Thus, the tongues 72, 73 of the two dot relays 60, 64 are connected direct to the positive terminal of the battery and their front contacts 74, 75 are connected together and to the winding 70 of the dot final relay. Thus, the tongues 72, 73 are in effect connected in parallel so that if due to fading one tongue fails to be attracted, the dot signal is not lost. It will be noticed that the tongue 76 of the dash relay 65 is connected to the positive of the battery and its front contact 77 is connected direct to the tongue 78 of the dash relay 61, while the front contact 79 of the latter is connected to the winding 71 of the dash final relay, so that in effect the tongues 76 and 78 are connected in series, so that if one of these tongues is operated on a dot signal due to fading, a false dash or space will not be perforated by the perforator controlled by the windings 70, 71.

The effect of atmospherics is different from the effects of fading, and consequently the four relays 60, 61, 64, 65 are differently connected to the final relays 70, 71 to deal with atmospherics. The mode of connection is illustrated in Figure 3 from which it will be noted that the tongues 72, 73 of the dot relays are now connected in series to the winding 71 of the final dot relay, while the tongues 76, 78 of the dash relays are now connected in parallel to the winding 70 of the final dash relay. Generally speaking, by suitable adjustment of the wireless apparatus it is possible to arrange that fading and atmospherics do not occur during the same period. In other words, during some periods the main trouble is due to fading, and during other periods it is due to atmospheric disturbances. Suitable change-over switches may be provided for changing over from the form of connections shown in Figure 2 to those shown in Figure 3 and in fact if desired the relays 60 and 61 or the relays 64, 65 only may be connected in circuit for fault testing purposes. Thus by providing a switch of the sun flower type with radial arms and circular rows of contact studs provided with four positions, the operator may at any time adopt the connection shown in Figure 2 or Figure 3 or connect in the relays 60 and 61 or the relays 64, 65 alone.

Sometimes it is necessary to make the interval between the original transmission and the repeated transmission so long that the form of storage by means of condensers illustrated in Figures 1 and 2 becomes cumbersome. In that case both in the transmitting apparatus and in the receiving apparatus a form of electromagnetic storage may be provided in the place of the condenser storage. This form of storage is shown as applied to the transmitting apparatus in Figure 4. The general circuit here is the same as in Figure 1. The relays TS, TD, combining switches C₁, C₂, the reversing switch RS, and all their contacts are similarly connected and similarly numbered. The only difference in Figure 4 is the storing arrangements. In Figure 4 the tongue 22 of the dot transmitter and the tongue 21 of the dash transmitter are respectively connected to terminals of the windings of secondary polarized relays 80, 81, the opposite terminals of which are connected together and earthed at 82. Thus, these secondary relays are operated when dots or dashes are transmitted and their tongues 75

83, 84 respectively close circuits through a source of interrupted direct current shown as a battery 85 and motor driven interrupter 86. The tongues 83, 84 and their contacts 87, 88 are respectively in the circuits of magnets 89 and 90 which may be termed respectively dot and dash recording magnets. They are placed so as to be capable of locally magnetizing a moving band 91 of magnetic material such as a soft iron telephone strip when the interrupted direct current is caused to pass through them. The strip 91 is led over a pair of pulleys 92 driven by a phonic motor 93 and is of such a length and driven at such a speed that the desired storage period may be obtained. It is arranged that the magnetic condition in the strip 91 corresponding to dots set up by the magnet 89 occurs on a distinct part of the strip from the magnetic condition representing dashes set up by the magnet 90 so that even if the magnetic condition, as it will be in this case, is the same for dots and dashes, this does not interfere with the operation. The strip after leaving the dot recording magnet 89 passes round until it reaches an electromagnetic pick-up or transmitter 94 for the dots. It then passes through a coil 95 fed with alternating current which demagnetizes it. Then in its virgin state it passes to the dash recording magnet 90 and then travels around until it reaches the dash pick-up or electromagnet transmitter 96 and then passes to a further demagnetizing coil 97 at which point it completes its cycle. The dot pick-up 94 and dash pick-up 96 are connected to separate amplifiers A₁, A₂ and separate rectifiers R₁, R₂. The output currents from the two rectifiers R₁, R₂ are supplied to the windings 12 and 13 of the two relays of the second set of cable code transmitting levers TD which is connected as in Figure 1. In this case, however, the relays 12, 13 are non-polarized since they have to be sensitive only to charge in the output rectified current from the rectifiers R₁, R₂.

A similar electromagnetic storing arrangement may be used at the receiving end to replace the condensers 55 in Figure 2, but the details of connections of such an electromagnetic storing device is clear without further description.

Other forms of electromagnetic storage comprising modifications of that described above may be employed, that is to say, the moving band may be replaced by a disc slowly rotated in synchronism, having, if desired, separate magnetic discs for dots and dashes, or a single magnetic disc may be employed with the magnetic conditions corresponding to dots and dashes stored in the iron at different radii from the centre of the disc.

The same frequency of interrupted direct current may be used for dots and dashes as already pointed out, but it follows that if a different frequency were provided for dashes than that provided for dots, if the amplifiers connected to the electromagnetic pick-ups were made selective to the respective frequencies, the same length of band or the same portion of the disc could be employed upon which the dot and dash electromagnetic recorders could be allowed to act.

In Figure 5 the use of yet another form of storage is illustrated. In this case the storage depends upon the actuation of the armatures of a number of polarized relays 97. It will be noticed that one side of the winding of each of these relays is connected to one of the distributor segments 14 upon which a pair of charging brushes 16, 17 bear as in Figure 1. The opposite termi-

nals of the relay windings are all earthed as shown at 98. When the dash charging brush 16 or the dot charging brush 17 makes contact with one of the segments 14, the corresponding relay 97 is momentarily energized and its tongue 99 is drawn over to the mark contact 100 or to the space contact 101—unless it were already there, and then remains against that contact. The tongues 99 of the relays are connected directly to the contact segments 15 which correspond to the discharging segments in Figure 1. The segments 15 may be made of any desired length circumferentially. The brushes 18 and 19 corresponding to the discharging brushes in Figure 1 are in this case connected directly to the contact 36 of the combining switch C₂ and to the contact 35 of the combining switch C₁. Actually the dot and dash distributor segments 14 and 15 may be arranged as two separate banks. In other respects the circuit shown in Figure 5 is the same as in Figure 1 and corresponding reference characters have been employed.

The use of the moving pin system of storage in connection with the present invention is illustrated in Figures 6 to 9. The rim of a drum has two raised circumferential flanges 102 shown developed in Figure 6. A series of pins 103 are mounted so as to slide axially in these flanges and make frictional engagement so that they remain in any axial position into which they are pushed. The polarized setting electromagnet 104 has a winding 105 and an armature 106 with an operating point 107. The drum 102 is rotated synchronously at such a rate that the time of angular movement from one of the pins 103 to move away from the point of the armature 106 and for the next pin to move opposite it, is equal to one signal interval. If the coil 105 is energized when a pin 103 arrives opposite to it the armature 106 is swung about its pivot 108 into the path of the pin 103 and the limb 107 acting as an inclined plane or cam, slides the pin 103 down into the position shown in Figure 6 at 103a. After a predetermined number of signal intervals, the pin is moved round until it comes opposite a spring returned lever 109 shown in plan in Figure 6 and in elevation in two positions in Figures 7 and 8. If the pin 103 has not been pushed down by the armature 106, it fails to contact with the lever 109 altogether and the latter remains in the position indicated in Figure 8. If, however, the pin 103 has been pushed into the position shown at 103a, the upper part of its cylindrical surface slides under the inclined nose 110 of the end of the lever 109 and raised this end against the tension of a spring 111 about a pivot 112. In this position, the lever 109 makes contact with a lower contact 114, otherwise as shown in Figure 7, it remains in contact with an upper contact 113.

In employing this device in a transmitter in accordance with the present invention, two such units are employed, the levers of which are shown in Figure 9 at 109a and 109b the two coils being shown at 105a and 105b. It will be noticed that these coils are connected respectively to the tongues 22 and 21 of the cable code transmitter relays while the opposite ends of both of the coils 105a and 105b are earthed. If a dot signal arrives, the coil 105a is energized and displaces the pin 103 which happens to be at that moment opposite its armature. Similarly if a dash signal arrives, the pin 103 in the drum actuated by the dash signals is displaced. As the two drums rotate and the pins come round, the levers 109a, 109b

109b are brought down on to their lower contacts 114a, 114b so that the positive and negative terminals of the split battery SB are respectively connected to the contact 35 of the combining switch C₁ and the contact 36 of the combining switch C₂. The transmitter TS is connected to these switches exactly as in Figure 1 and these switches in turn are connected to the reversing switch RS in the same way as in Figure 1.

10 We claim:—

1. A telegraph signaling system for receiving double current cable code signals of the type set forth, comprising in combination, a receiving relay for receiving a transmission of signals 15 on one channel and a delayed transmission of signals on a separate channel, switching means for converting both transmissions of double current cable code signals into cable code signals, a signal impulse storage device operatively connected to said switching means for receiving and storing the undelayed transmission and a receiving apparatus for receiving the signals of the first transmission released from said storage device and the signals of the delayed transmission 25 from said switching means.

2. A telegraph signaling system for receiving double current cable code radio signals consisting of dots, each represented by power transmission enduring for a whole signal period, of dashes, 30 each represented by ceasing to transmit power for a whole signal period, and of spaces, each represented by power transmission enduring for part of a signal period followed by ceasing to transmit power for the remainder of said signal 35 period, comprising a receiving relay, switching gear driven in step with the received signal periods for converting said double current cable code signals into cable code signals, a pair of relays connected to said switching gear to be actuated by signals of one channel, a second pair of relays connected to be actuated by the signals of a second channel, a signal impulse storage device operatively connected to receive and store the signal impulses from said first-named pair of 40 relays, a pair of comparison relays for receiving respectively the dot and dash signals from said storage device, a second pair of comparison relays for receiving respectively the dot and dash signals of the second channel without storage, a receiving apparatus connected to the contacts of said comparison relays and means for actuating said receiving apparatus to be actuated under the control of the signals of both channels.

55 3. A telegraph signaling system for receiving double current cable code radio signals consisting of dots, each represented by power transmission enduring for a whole signal interval, of dashes, each represented by ceasing to transmit power for a whole signal interval, and of spaces, each represented by power transmission enduring for part of a signal interval followed by ceasing to transmit power for the remainder of said signal interval, comprising a receiving relay, switching 60 gear driven in step with the received signal periods for converting said double current cable code signals into cable code signals, a pair of relays connected to said switching gear to be actuated by signals of one channel, a second pair of relays connected to be actuated by the signals of a second channel, a signal impulse storage device operatively connected to receive and store the signal impulses from said first-named pair of relays, a pair of comparison relays for receiving 65 respectively the dot and dash signals from said

storage device, a second pair of comparison relays for receiving respectively the dot and dash signals of the second channel without storage, a receiving apparatus connected to the contacts of said comparison relays and actuated under the control of the signals of both channels, and a switching device for selectively connecting on the one hand the contacts of the pair of dot comparison relays in parallel and the contacts of the pair of dash comparison relays in series and, on the other hand, connecting the contacts of the pair of dot comparison relays in series and the contacts of the pair of dash comparison relays in parallel.

4. A multi-channel telegraph signaling system for receiving double current cable code signals of the type set forth, comprising in combination, a receiving relay, switch means for converting the double current cable code signals into cable code signals and for separating said signals according to their respective transmission channels, a signal impulse storage device comprising a set of condensers and switching gear driven in step with the received signal periods for charging and discharging said condensers, said storage device being connected to be responsive to the signals of one channel and a receiving apparatus common to both channels and connected to receive the signals of one channel released from said storage device and the signals of said other channel from said switch means without storage.

5. A telegraph signaling system for operation with double current cable code signals of the type set forth, comprising in combination, a cable code transmitter, a signal impulse storage device operatively connected to said transmitter, means for sending-on signals from said cable code transmitter and said storage device, switching gear driven in step with the signal periods connected to said cable code transmitter, said storage device and said sending-on means and organized to close contacts to control the electrical condition of said sending-on means so that double current cable code signals are sent on from said transmitter and are repeated, after a predetermined time delay, from said storage device, a receiving relay for receiving the undelayed and repeated transmissions of the double current cable code signals, switching means for converting both of said transmissions into cable code signals, a second signal impulse storage device operatively connected to said switching means for receiving and storing said undelayed transmission, a receiving apparatus common to both of said transmissions and means connecting said receiving device for receiving the signals of the first transmission released from said second storage device and the signals of the delayed transmission from said switching means.

6. A multi-channel telegraph signaling system for operation with double current cable code signals of the type set forth, comprising in combination, a plurality of cable code transmitters actuated in synchronism with the signals, a signal impulse storage device operatively connected to store signal impulses from one of said cable code transmitters and to pass on said signal impulses after a predetermined time delay to a second cable code transmitter, means for sending-on signals from said transmitters switching gear driven in step with the signal periods organized to pass on the signals from said cable code transmitters to said sending-on means in the form of double-current cable code signals and to allocate the signals

from the respective cable code transmitters to separate channels in a predetermined sequence, a receiving relay, switching means driven in step with the received signal periods for converting the double current cable code signals into cable code signals and for separating said signals according to their respective transmission channels, a second signal impulse storage device operatively connected to said switching means to be responsive to the signals of one channel and a receiving apparatus common to a plurality of channels and connected to receive the signals of one channel released from said second storage device and the signals of another channel from said switch means without storage.

7. A multi-channel telegraph signaling system for operation with double current cable code signals of the type set forth, comprising in combination, a plurality of cable code transmitters actuated in synchronism with the signals, means for sending-on signals from said transmitters, a signal impulse storage device comprising a plurality of storage condensers, a plurality of contact segments connected to said condensers, and condenser charging and discharging brushes relatively driven, said charging brushes being connected to one of said cable code transmitters and said discharging brushes to a second cable code transmitter so as to pass on signal impulses stored in said condensers to said second cable code transmitter after a predetermined time delay and switching gear driven in step with the signal periods organized to pass on the signals from said cable code transmitters to said sending-on means in the form of double current cable code signals and to allocate the signals from the respective cable code transmitters to separate channels in a predetermined sequence, a receiving relay, switching means driven in step with the received signal periods for converting the double current cable code signals into cable code signals and for separating said signals according to their respective transmission channels, a second signal impulse storage device operatively connected to said switching means to be responsive to the signals of one channel and a receiving apparatus common to a plurality of channels and connected to receive the signals of one channel released from said second storage device and the signals of another channel from said switch means without storage.

8. A multi-channel telegraph signaling system for operation with double current cable code signals of the type set forth, comprising in combination, a pair of signaling devices for producing respectively dot and dash cable code signals, an electro-magnetic signal impulse storage device having input circuits connected respectively to

said signaling devices, a further pair of signaling devices respectively connected to the output circuits of said storage device, means for sending-on signals produced by said signaling devices, switching gear driven in step with the signal periods organized to pass on the signals from said signaling devices to said sending-on means in the form of double current cable code signals and to allocate the signals from the respective pairs of signaling devices to separate channels in a predetermined sequence, a receiving relay, switching means driven in step with the received signal periods for converting the double current cable code signals into cable code signals and for separating said signals according to their respective transmission channels, a second signal impulse storage device operatively connected to said switching means to be responsive to the signals of one channel and a receiving apparatus common to a plurality of channels and connected to receive the signals of one channel released from said second storage device and the signals of another channel from said switch means without storage.

9. A multi-channel telegraph signaling system for operation with double current cable code signals of the type set forth, comprising in combination, a pair of signaling devices for producing respectively dot and dash cable code signals, a mechanical storage device for the signal impulses comprising a plurality of movable members, a pair of electromagnets allocated to dots and dashes respectively for setting said members and a pair of contact-closing levers cooperating with said members, means for sending-on the signals produced, switching gear driven in step with the signal periods organized to pass on the signal impulses from said signaling devices and from said contact-closing levers to said sending-on means in the form of double current cable code signals, the signals from said contact levers being passed on after a predetermined time delay, a receiving relay, switching means driven in step with the received signal periods for converting the double current cable code signals into cable code signals and for separating said signals according to their respective transmission channels, a second signal impulse storage device operatively connected to said switching means to be responsive to the signals of one channel and a receiving apparatus common to a plurality of channels and connected to receive the signals of one channel released from said second storage device and the signals of another channel from said switch means without storage.
